Attorney

UNITED STATES PATENT OFFICE.

ALLEN E. CHISHOLM AND SAMUEL MURRAY, OF PORTLAND, OREGON; SAID MURRAY
ASSIGNOR TO SAID CHISHOLM.

OIL BURNER.

Application filed December 29, 1922. Serial No. 609,660.

To all whom it may concern:

Be it known that we, ALLEN E. CHISHOLM and SAMUEL MURRAY, citizens of the United States, residing at Portland, in the county of Multnomah and State of Oregon, have invented certain new and useful Improvements in Oil Burners, of which the following is a specification.

This invention relates to improvements in oil burners, and has particular reference to that type of oil burner in which liquid fuel, such as crude oil or the like, and a supporter of combustion, such as steam, or air, or both, are thoroughly mixed within the burner to produce a highly combustible mixture capable of generating intense heat upon ignition.

The object of this invention is to provide an oil burner in which the liquid fuel is, by impact and capillary attraction, changed into an extremely thin sheet of liquid fuel, which is then subjected to the atomizing action of steam, whereby the fuel is shattered and finely atomized, and this mixture then passed into a suitable expansion chamber to more completely utilize the atomizing and expanding of the fuel oil and steam.

A further object of the invention is to provide an oil burner in which an auxiliary jet of steam is employed in connection with a Venturi tube, whereby the aforesaid mixture of fuel oil and steam is drawn under high velocity from said expansion chamber, past the sharp edges of a contracted discharge passage, and mixed with suitable quantities of air to produce a highly combustible mixture.

A further object of the invention is to provide a device of the above mentioned character in which the parts of the burner structure are readily detachable so that access may be had to the interior of the burner for purposes of cleaning and repair.

A still further object of this invention is to provide a device of the above mentioned character that is simple in construction, convenient in use, strong and durable, and highly efficient in the purpose for which designed.

In the accompanying drawings, forming a part of the specification, and in which like numerals are employed to designate like parts throughout the several views:

Figure 1 is a vertical sectional view of our improved burner, and

Figures 2, 3 and 4 are transverse sectional views on the lines 2—2, 3—3, and 4—4 respectively of Figure 1.

Referring to the drawings, wherein for the purpose of illustration is shown a preferred embodiment of the invention, the numeral 5 represents the oil inlet to the burner and comprises an elbow construction through the vertical passage of which extends the needle-valve stem 6. Secured to this elbow is the oil nozzle 7, provided near the base of its central passage with a valve seat adapted to coat with the valve stem 6 to regulate the amount of oil fed to the burner. Connected to the nozzle 7 is the expansion and vaporizing bowl, comprising the lower cup-shaped section 8, and the upper dome-like section 9, detachably connected to the section 8 by suitable bolts 10. The member 8 is provided near its base with steam inlet 11 and is constructed to form an annular opening 12 concentric with the oil nozzle 7. Attached to the upper section 9 of the bowl, and supported by the spider 13 is a deflector plug 14, having a lower concaved surface 15, against which the oil from nozzle 7 impinges. The rim of this concaved surface 15 flares outwardly, as indicated at 16, and then flares inwardly to form the contracted portion 17, slightly spaced from the correspondingly shaped wall 18 of the upper bowl member 9, to form a sharp edged contracted discharge passage 19.

Secured to the upper open end of the expansion and vaporizing bowl and preferably at right angles to the same is the mixing tube 20, provided at one of its ends with the steam injector nozzle 21, and near its opposite end with primary air inlet openings 22, radially arranged in series about the tube. Positioned within the tube 20 at a point in rear of the openings 22, is the inwardly tapering cone 23 of a Venturi tube. Secured to the outer end of the said mixing tube 20 is the outwardly tapered cone 24 of the Venturi tube, the inner end of said cone being slightly spaced from the discharge end of the cone 23 to provide means of communication with the primary air openings 22 above referred to. The outer member 24 of the Venturi tube is further provided with auxiliary air inlet openings 25 arranged radially through the walls of the same.

It is thus obvious from the above detailed description of construction and assembly,

and also from the accompanying drawings, that we have provided an oil burner structure in which the various parts are readily detachable to provide access to the interior 5 of the burner for purposes of cleaning and repair.

In the operation of the above described burner, oil under pressure is fed in at the oil inlet 5, the amount of such fuel being 10 regulated by the needle-valve 6. This liquid fuel passes upwardly through the nozzle 7 and is ejected against the center of the concaved surface 15 of the deflector plug 14, whereby the cylindrical stream of fuel 15 is, by impact and capillary attraction, changed into an extremely thin dome-like sheet of liquid fuel which is discharged from the outer rim of the concaved surface. This action is the initial step toward atomizing 20 the oil. High pressure super-heated steam is admitted through the steam inlet 11 and passes through the annular passage 12, discharging in the form of a hollow cylindrical jet which strikes against the thin 25 sheet of fuel oil, a short distance from the rim of the concaved surface, 15, whereby the fuel oil is shattered by the impact of the steam and finely atomized. This mixture of atomized fuel and steam passes into 30 the vaporizing and expansion bowl and is violently thrown against the curved inner wall of the same, which imparts a whirling motion to the mixture, the impact and whirling, together with the high temperature, 35 serving to further break up the oil particles. Due to the enlarged diameter of the vaporizing and expansion bowl, the oil and steam thoroughly commingle, and herein takes place the initial expansion of the 40 atomized mixture.

Simultaneously with the admission of oil and steam through the inlets 5 and 11 respectively, steam, preferably superheated, is admitted through the auxiliary steam nozzle 45 21 into the mixing tube 20. This creates a partial vacuum within the tube 20 and draws the whirling mixture from the expansion and vaporizing bowl, past the sharp edges of the passage 19, which causes a further 50 breaking-up of the particles of oil. This mixture then passes through the contracted discharge passage 19 into the mixing tube 20, where it contacts with the high pressure steam ejecting from the nozzle 21, 55 which further increases the velocity of the mixture as it passes into the Venturi tube 23. The passage of the mixture through the Venturi tube creates a partial vacuum at the throat of the same, and, due to the 60 spaced relation of the members 23 and 24 of the tube, air is drawn through the primary air inlet openings 22 and becomes intimately mixed with the combined oil and steam to produce a highly combustible mixture. The supply of air is further increased 65

and the combustible properties of the mixture materially improved by the arrangement of the auxiliary air inlet openings 25 through which additional air is drawn as the mixture passes through the tube section 24. Accordingly, when once ignited, 70 this highly combustible mixture will burn with great heat and intensity, ignition taking place a few inches past the tip of the tube 24. 75

It is to be understood that the form of our invention herewith shown and described is to be taken as a preferred embodiment of the same and that various changes in the shape, size and arrangement of parts may 80 be resorted to without departing from the spirit of the invention or the scope of the subjoined claims.

Having thus described our invention, 85 what we claim as new and desire to secure by Letters Patent is:—

1. An oil burner comprising an expansion and vaporizing chamber, an oil inlet within the chamber, an abutment within the chamber to intercept the flow of oil and spread the same outwardly and rearwardly, a steam inlet to said chamber for directing steam in an annular stream toward and into the rearwardly projected oil subsequent to its contact with said abutment to atomize 95 the same, and means communicating with the chamber for drawing the atomized mixture from said chamber, and forcibly ejecting the mixture from the burner. 100

2. An oil burner comprising an expansion and vaporizing bowl having a sharp-edged annular discharge opening, an oil inlet within the bowl, an abutment within the bowl to intercept the flow of oil and spread the same, a steam inlet to said bowl for directing steam toward and into the oil subsequent to its contact with said abutment to atomize the same and to impart a whirling motion to the mixture within the bowl, and means communicating with the bowl 110 for drawing the whirling mixture from the chamber through the sharp-edged discharge opening and combining the mixture with suitable quantities of air to produce a highly combustible mixture. 115

3. An oil burner, comprising an expansion and vaporizing bowl wherein fuel oil is atomized, and a mixing tube communicating with said bowl in which the atomized vapor is subjected to the action of an auxiliary jet of steam to more completely atomize the vapor and to forcibly eject the same from the burner, a Venturi tube through which the vapor is projected and provided with air openings adjacent the throat for admitting air to the atomized vapor. 120

4. An oil burner, comprising an expansion and vaporizing bowl wherein fuel oil is atomized, said bowl having a sharp-edged annular discharge opening; and a mixing 125

5 tube communicating with said bowl into which the atomized vapor drawn through the sharp-edged annular discharge opening is subjected to the action of an auxiliary jet of steam to more completely atomize the vapor and to forcibly eject the same from the burner, a Venturi tube through which the vapor is projected and provided with air openings adjacent the throat for admitting 10 air to the atomized vapor.

5. An oil burner comprising an expansion and vaporizing chamber wherein fuel oil is atomized, a mixing tube communicating with said chamber in which the atomized vapor is subjected to the action of an auxiliary jet of steam to more completely atomize the vapor and to forcibly eject the same from the burner, a Venturi tube through which the vapor is projected and provided 15 with air openings adjacent the throat for admitting air to the atomized vapor.

6. An oil burner comprising an expansion and vaporizing chamber in which fuel oil is atomized, a Venturi tube communicating with said chamber, and means for drawing the atomized vapor from said chamber and forcibly ejecting the same through said Venturi tube, said Venturi tube being provided with air openings adjacent the throat for admitting air to the atomized vapor.

7. An oil burner comprising an expansion and vaporizing chamber in which fuel oil is atomized, a Venturi tube communicating with said chamber; means for drawing the atomized vapor from said chamber and forcibly ejecting the same through said Venturi tube, and means for supplying a supporter of combustion at the throat of said venturi to said atomized vapor as it passes through said Venturi tube.

8. An oil burner comprising a chamber in which fuel oil is atomized; a Venturi tube communicating with said chamber, said tube having air inlet openings through the wall thereof adjacent the throat of said venturi; and means for drawing the atomized vapors from said chamber and forcing the same

through said tube, whereby the atomized vapor is supplied with air.

9. An oil burner comprising a chamber in which fuel oil is atomized; a Venturi tube communicating with said chamber, said tube having a primary air inlet opening near the throat thereof and an auxiliary air inlet opening beyond said primary inlet; and means for drawing the atomized vapor from said chamber and forcing the same through said tube, whereby air is drawn through said inlet openings and thoroughly mixed with the atomized vapor to produce a highly combustible mixture.

10. An oil burner comprising a chamber in which fuel oil is atomized; a two-part Venturi tube communicating with said chamber and comprising an inner and outer cone, the two-part tube being provided with openings to form annular air inlet openings at the throat of the tube; and means for drawing the atomized vapor from said chamber and forcing the same through said tube, whereby air is drawn through said annular openings and mixed with the atomized vapor to produce a highly combustible mixture.

11. In an oil burner the combination of a casing, an oil inlet to said casing, an abutment within the casing to intercept the flow of oil and spread the same, an annular steam inlet to said casing arranged concentric to said oil inlet for directing the steam toward and into the oil subsequent to its contact with said abutment, a Venturi tube provided with openings adjacent the throat thereof, and means communicating with said casing for drawing the atomized mixture from said casing and mixing said atomized mixture with suitable quantities of air from the openings adjacent the throat to produce a highly combustible mixture.

In testimony whereof we hereunto affix 90 our signatures.

ALLEN E. CHISHOLM.
SAMUEL MURRAY.
